UNITED STATES PATENT OFFICE.

HARRY L. GUY, OF OAK PARK, ILLINOIS, ASSIGNOR OF ONE-HALF TO CHARLES S. PURNELL, OF OAK PARK, ILLINOIS.

ROOFING.

Application filed September 13, 1924. Serial No. 737,610.

My invention relates to improvements in roofing and is particularly concerned with the provision of a novel type of roofing formed of a plurality of shingles, preferably 5 formed from sheets of fibrous material, impregnated or coated, or both, with material capable of repelling water.

The objects of my invention are:

First, to provide roofing in the form of 10 shingles that are of such size and so shaped that they can be easily applied and secured to a roof;

Second, to provide shingles, such as described, having straight lateral edges adapt- 15 ed to abut the corresponding edges of shingles in the same course, so as to enable the workman laying the shingles easily to maintain straight courses without the necessity of resorting to straight edges or guide lines;

20 Third, to provide roofing, such as described, comprising a plurality of courses of shingles, each of which overlies the next lower course, the shingles of each course being provided with means for interlocking 25 with the adjacent shingles in the next lower course in such manner as to prevent the shingles from curling up under the influence of heat or moisture and to prevent the shingles from being deformed or torn loose by the 30 wind;

Fourth, to provide roofing, of the character described, in which a minimum number of nails or fastening devices is required for holding the shingles in position;

35 Fifth, to provide roofing, of the character described, in which the shingles of each course cover the fastening means in the shingles of the next lower course;

Sixth, to provide roofing, such as de- 40 scribed, in which the edges of the shingles define geometrical figures that are pleasing to the eye, these figures preferably being in the shape of a hexagon;

Seventh, to provide a roofing in which the 45 lower inclined edges of the shingles in each course are substantially parallel with and overlap the inclined upper edges of the shingles of the next lower course sufficiently to provide adequate means for preventing 50 rain or snow from being blown between two adjacent courses of shingles;

Eighth, to provide roofing, of the character described above, in which the shingles of each course break joints with the shingles 55 of the next lower course and are provided

with a sealing strip for preventing rain from being blown between the abutting edges of the shingles in the next lower course; and

Ninth, to provide a shingle and a roofing 60 construction such as described above that is simple, economical to manufacture and easy to lay.

Other objects of my invention will appear as this description progresses, reference being had to the accompanying drawings, in 65 which

Figure 1 is a side elevation of a roof embodying my invention;

Figure 2 is a view similar to Figure 1 70 with parts broken away for the purpose of better illustration; and

Figure 3 is a perspective view of one of 75 my improved shingles.

Throughout the several views similar reference characters are used for referring to similar parts.

My improved shingle, by which the roofing shown in Figures 1 and 2 is formed, comprises a substantially rectangular piece 80 of roofing material, preferably of the so-called prepared roofing, comprising a flexible, fibrous sheet impregnated with a water-repellent material and coated with any of the various materials now used for coating 85 such fibrous materials.

Two of the oppositely disposed corners of my improved shingle are truncated, or cut off, to form the edges 5 which, when a plurality of these shingles is laid to form 90 a roof, abut the corresponding edges of the adjacent shingles to assist the workman properly to align the shingles in each course. Another one of the corners of the rectangular piece of material has a sealing strip 6 95 formed integrally therewith. The ends 6' of this sealing strip project beyond the adjacent diagonal edges 7 of the shingle for a purpose that will later be referred to. V-shaped notches or recesses 8 are cut in the 100 shingle immediately beneath the truncated corners or edges 5, as shown in Figure 3.

In applying the shingles just described, a strip 9 of prepared roofing material is first laid along the lower edge of the roof. 105 This strip of material is slightly narrower than the longest diagonal of the shingle.

A course of shingles is then laid upon the strip of material with the lower edges 110 substantially flush with the edge of the

roof. I prefer to cut off the projecting ends 6' of the sealing strip of this lower course of shingles in alignment with the lower diagonal edges 7 of the shingles, so as to 5 give hexagonal outlines to those portions of the strip 9 lying between adjacent shingles that are exposed to view.

The workman then takes another shingle and lays it so that the sealing strip 6 lies 10 between the inclined edges 7 of two adjacent shingles. Then, by lifting these inclined edges and pulling upwardly upon the shingle that is being laid, the projecting ends 6' of the sealing strip are moved upwardly 15 beneath the inclined edges 7 until the inclined edges of the sealing strip engage the horizontal edges 11 of the two adjacent shingles. He then repeats this process until the next course is formed and proceeds in 20 this manner to lay as many courses as may be required for covering the roof.

The ridge of the roof may be covered by a strip or roll 12 of suitable ridge material, such as prepared roofing sheet material, etc.

25 For the purpose of holding the shingles in position after being applied, I make use of nails 13, or other suitable fastening means, that are driven through the truncated corners at substantially points indicated by 30 the reference characters 14 in Figure 3. These nails pass through the upper ends of the shingles of the next lower course, as shown in Figure 2.

A roof formed of my novel shingles in 35 the manner described above has the appearance of being formed of a plurality of hexagonal figures, as shown in Figure 1, and serves to break up the monotonous appearance of the roof that would result if it were 40 formed of plain strips of roofing.

It will be apparent that the sealing strip 6 not only provides means for interlocking the lower end of each shingle with the shingles of the next lower course, thus 45 preventing the lower ends of the shingles from curling upwardly or being blown upwardly by the wind, but also provides means for sealing the abutting edges 5 of the shingles in the next lower course 50 so as to prevent rain from being blown up between these abutting edges. It should also be observed that the lower diagonal edges 7 of each shingle are substantially parallel with the upper diagonal edges of the shingles 55 in the next lower row and overlap these edges a substantial distance so as to efficiently exclude rain, snow, dust, etc.

It is easy to lay my improved shingle and it requires a minimum of material for 60 covering a given area, so that it is economical both in material and in the labor required to lay it.

While I have described the details of construction of the preferred embodiment of 65 my invention it is to be understood that my

invention is not limited to these details, but is capable of other adaptations and modifications within the scope of the appended claims.

Having thus described my invention, what 70 I claim is:

1. A roof comprising a plurality of courses of shingles arranged in overlapping relation, with the shingles in each course breaking joints with the shingles in the next 75 lower course; each of said shingles comprising a substantially rectangular piece of prepared roofing positioned with one of its diagonals in a vertical plane, the lateral corners of each of said shingles being truncated 80 to provide vertical, abutting, aligning edges, said shingles each having a recess formed in each side thereof immediately below the truncated corner thereof the upper side of each of said recesses intersecting the 85 adjacent aligning edge; the lower ends of said shingles each terminating in a sealing strip having its ends projecting into the recesses in the underlying shingles of the 90 next course; the lower diagonal edges of the shingles in one course being substantially 95 parallel with the upper diagonal edges of the next lower course.

2. A roof comprising a plurality of courses of shingles arranged in overlapping relation, with the shingles in each course breaking joints with the shingles in the next lower course; each of said shingles comprising a substantially rectangular piece of material positioned with one of its diagonals 100 in a vertical plane, the lateral corners of each of said shingles being truncated to provide vertical, abutting, aligning edges, said shingles each having a recess formed in each side thereof below the truncated corner 105 thereof the upper side of each of said recesses intersecting the adjacent aligning edge; the lower ends of said shingles each terminating in a sealing strip having its ends projecting into the recesses in the underlying 110 shingles of the next course.

3. A roof comprising a plurality of courses of shingles arranged in overlapping relation, with the shingles in each course breaking joints with the shingles in the next lower 115 course; each of said shingles comprising a substantially rectangular piece of prepared roofing positioned with one of its diagonals in a vertical plane, the lateral corners of each of said shingles being truncated to provide vertical, abutting, aligning edges; the lower ends of said shingles each terminating in a sealing strip having its ends projecting beneath the lower diagonal edges of the adjacent shingles in the next lower course; the ends of said sealing strip being inclined in directions opposite to the directions of inclination of the adjacent edges of said shingle.

4. An article of manufacture comprising 120

- 1 a substantially rectangular piece of prepared
2 roofing material having two diagonally dis-
3 posed corners truncated to form aligning
4 edges, one of the other corners having a seal-
5 ing strip formed integrally therewith, said
6 sealing strip having ends projecting beyond
7 the adjacent edges of said shingle, there
8 being recesses formed in the edges of said
9 shingles immediately beneath said truncated
10 corners, the upper side of each recess inter-
11 secting the adjacent aligning edge.

12 5. An article of manufacture comprising
13 a substantially rectangular piece of roofing
14 material having two diagonally disposed
15 corners truncated to form aligning edges,
16 one of the other corners having a sealing
17 strip formed integrally therewith, said seal-
18 ing strip having ends projecting beyond the
19 adjacent edges of said shingle, there being
20 recesses formed in the edges of said shingles
21 immediately beneath said truncated corners,
22 the lower side of each of said recesses being
23 substantially parallel with the lower in-
24 clined edge of the opposite side of said
25 shingle.

26 6. An article of manufacture comprising
27 a substantially rectangular piece of prepared
28 roofing material having two diagonally dis-
29 posed corners truncated to form aligning
30 edges, one of the other corners having a seal-
31 ing strip formed integrally therewith, said seal-
32 ing strip having ends projecting beyond the
33 adjacent edges of said shingles, there being
34 V-shaped recesses formed in the
35 edges of said shingles immediately beneath
36 said truncated corners, the lower side of each
37 of said recesses being substantially parallel
38 with the lower inclined edge of the opposite
39 side of said shingle.

40 7. A roof comprising a plurality of
41 courses of shingles arranged in overlapping
42 relation, with the shingles in each course
43 breaking joints with the shingles in the next
44 lower course; each of said shingles comprising
45 a piece of prepared roofing positioned
46 with one of its diagonals in a vertical plane,
47 the lateral corners of each of said shingles
48 being truncated to provide vertical, abut-
49 ting, aligning edges, said shingles each hav-
50 ing a recess formed in each side thereof im-
51 mediately below the truncated corner
52 thereof, the upper side of each of said re-
53 cesses intersecting the adjacent aligning
54 edge; the lower ends of said shingles each
55 terminating in a sealing strip having its
56 ends projecting into the recesses in the un-
57 derlying shingles of the next course; the
58 lower diagonal edges of the shingles in one
59 course being substantially parallel with the
60 upper diagonal edges of the next lower
61 course.

62 8. A roof comprising a plurality of
63 courses of shingles arranged in overlapping
64 relation, with the shingles in each course
65 breaking joints with the shingles in the next
66 lower course; each of said shingles com-
67 prising a piece of material positioned with
68 one of its diagonals in a vertical plane, the
69 lateral corners of each of said shingles being
70 truncated to provide vertical, abutting,
71 aligning edges, said shingles each having a
72 recess formed in each side thereof below the
73 truncated corner thereof, the upper side of
74 each of said recesses intersecting the ad-
75 jacent aligning edge; the lower ends of said
76 shingles each terminating in a sealing strip
77 having its ends projecting into the recesses
78 in the underlying shingles of the next
79 course.

80 9. A roof comprising a plurality of
81 courses of shingles arranged in overlapping
82 relation, with the shingles in each course
83 breaking joints with the shingles in the next
84 lower course; each of said shingles com-
85 prising a piece of prepared roofing posi-
86 tioned with one of its diagonals in a verti-
87 cal plane, the lateral corners of each of said
88 shingles being truncated to provide vertical,
89 abutting, aligning edges; the lower ends of
90 said shingles each terminating in a sealing
91 strip having its ends projecting beneath the
92 lower diagonal edges of the adjacent shin-
93 gles in the next lower course; the ends of
94 said sealing strip being inclined in direc-
95 tions opposite to the directions of inclina-
96 tion of the adjacent edges of said shingle.

97 10. An article of manufacture comprising
98 a piece of prepared roofing material
99 having two diagonally disposed corners
100 truncated to form aligning edges, one of
101 the other corners having a sealing strip
102 formed integrally therewith, said sealing
103 strip having ends projecting beyond the
104 adjacent edges of said shingle, there being
105 recesses formed in the edges of said shin-
106 gles immediately beneath said truncated
107 corners, the upper side of each recess inter-
108 secting the adjacent aligning edge.

109 11. A roof comprising a plurality of gen-
110 erally quadrilateral shingles laid with one
111 diagonal running up and down the roof, the
112 bottom corner of each shingle having in-
113 tegral lateral projections to lock under ad-
114 jacent lower shingles, and the side corners
115 of said shingles being truncated to leave
116 vertical edges, the vertical edges of the shin-
117 gles in the same row abutting to maintain
118 alignment.

119 In witness whereof, I hereunto subscribe
120 my name this 9th day of September, 1924.

HARRY L. GUY.

In witness whereof, I hereunto subscribe my name this 9th day of September, 1924.

HARRY L. GUY.
